UNITED STATES PATENT OFFICE.

EMIL MATTMAN, OF WILKINSBURG, PENNSYLVANIA, ASSIGNOR TO WESTINGHOUSE ELECTRIC AND MANUFACTURING COMPANY, A CORPORATION OF PENNSYLVANIA.

BRUSH-LIFTING DEVICE FOR DYNAMO-ELECTRIC MACHINES.

1,089,142.

Specification of Letters Patent. Patented Mar. 3, 1914.

Application filed June 21, 1912. Serial No. 705,072.

To all whom it may concern:

Be it known that I, EMIL MATTMAN, a citizen of Switzerland, and a resident of Wilkinsburg, in the county of Allegheny and State of Pennsylvania, have invented a new and useful Improvement in Brush-Lifting Devices for Dynamo-Electric Machines, of which the following is a specification.

My invention relates to dynamo-electric machines, and it has for its object to provide means for temporarily lifting the brushes of a dynamo-electric machine out of engagement with the commutator cylinder which means shall be effective and reliable in operation and will not cause breakage of the brushes.

The invention is particularly useful in connection with rotary converters and similar synchronous machines which have main and auxiliary field poles and are adapted to be started by current received from an alternating current circuit.

My invention is illustrated in the accompanying drawings, Figure 1 of which is an end view of a part of a machine constructed in accordance therewith. Fig. 2 is a side and sectional view of a part of the said machine, Fig. 3 is an enlarged side view of some of the parts that coöperate with the brush to raise it, and Figs. 4, 5, 6, 7, 8 and 9 are detail views of the parts shown in assembled relation in the preceding figures.

The invention is here shown as employed in connection with a rotary converter having a field frame 1 provided with main and auxiliary polar projections 2 and 3, respectively, and with a recess or seat in its end face for the reception of a two-part rocker ring 4. The rocker ring serves as a support for a plurality of regularly spaced laterally and radially extending brackets 5, that are secured thereto but are insulated therefrom, each of said brackets comprising a bar 6 that extends parallel to, and is spaced a suitable distance from, the commutator cylinder 7 of the machine. Each of the bars 6 carries a plurality of side by side brush holders 8 that are rigidly secured thereto and comprise guides for brushes 9 that bear upon, and are resiliently maintained in engagement with, the commutator cylinder by means of springs 10.

The inner circumferential face of the rocker ring 4 is provided with a recess for the reception of an outer circumferential

boss 11 upon another ring 12, which may be rotated with respect to the rocker ring by means of a lever 13 that is pivoted to the rocker ring and has a slot and pin connection with the inner ring 12. The ring 12 carries a plurality of regularly spaced arms or brackets 14 respectively adjacent to the brush holder supports, the said brackets being suitably insulated from the ring. Each of the brackets 14 is provided at its end with an adjustable clamp for a radially extending rod 15 that is provided at its free end with a laterally projecting pin 16. The said pin is embraced by the bifurcated end of an arm 17 that is rigidly attached at its other end to a rod 18 that extends parallel to the brush holder supporting bar 6 and is rotatably mounted in small brackets 19 carried thereby. Secured to the rod 18 at regular intervals are a plurality of resilient substantially Z-shaped clips or arms 20, the free ends of which project toward, and are adjacent to, the respective brushes, and are provided with small pivotally supported pawls 21 that are normally maintained in the positions shown by means of springs 22. The pawls 21 are adapted to engage the teeth of ratchets 23 that are respectively secured to the outer ends of the brushes and extend substantially radially therefrom.

In order to raise the brushes out of engagement with the commutator cylinder, the operating lever 13 is rotated in a counter clockwise direction, resulting in a clockwise rotation of the inner ring 12 and of the radially extending rods 15, the new position of one of the radially extending rods being shown in broken lines in Fig. 1. The rods 15 in turn cause rotation of the bifurcated arms 17 and rotation of the resilient pawl-carrying arms 20 in a clockwise direction. The pawls 21 are thus brought into engagement with the teeth of the ratchets with the result that the brushes are moved outwardly and out of engagement with the commutator cylinder. The resilience of the pawl-carrying arms, and the resilient pivotal mounting of the pawls, insure reliable and effective engagement of the pawls with the ratchets, and relieve the brushes of undue transverse strains, so that there is little or no liability of breakage thereof. When the machine has attained synchronous speed, the operating lever is again moved to the position shown, whereupon the pawls will become disengaged.

gaged from the ratchets, and the brushes will be returned into engagement with the commutator cylinder by means of the springs 10.

5 I claim as my invention:

1. A brush-lifting device for dynamo-electric machines comprising a brush holder, a brush supported thereby, a ratchet carried by the brush, a resiliently mounted pawl adapted to engage the ratchet, and means for actuating the pawl to move the brush in the holder.
- 10 2. A brush-lifting device for dynamo-electric machines comprising a brush holder, a spring-actuated brush supported thereby and provided with a ratchet, a resiliently mounted pawl, and means for effecting op-

erative engagement of said pawl with said ratchet for moving the brush in the holder.

3. A brush-lifting device for dynamo-electric machines comprising a brush holder, a brush supported thereby, a ratchet carried by the brush, a pawl adapted to engage the ratchet, a resilient arm to which the pawl is pivoted, and means for actuating the said 25 arm to move the brush in the holder.

In testimony whereof, I have hereunto subscribed my name this 17th day of June, 1912.

EMIL MATTMAN.
